FORMING APPARATUS

Jacob D. Stiriss, New York, N. Y.

Application January 30, 1943, Serial No. 474,203

2 Claims. (Cl. 153—46)

This invention relates to forming apparatus, and more particularly to apparatus for forming or bending partially enclosed channel members, such as channel members used for turret rail tracks, into a desired accurate shape, for instance, circular shape, while assuring that each element of the rail track has an accurately alike profile cross section.

Among the objects of the invention is an apparatus for providing the border portions of such rails with grooves or serrations uniformly distributed along the length of the rail track, while assuring that the relation of the profile of each groove or the root thereof to an adjacent wall element of the channel is maintained within certain close limits of tolerance, notwithstanding the fact that the general dimensions of the rail member vary within a wider range of tolerance.

Among the objects of the invention is also an apparatus for forming a given channel of a given shape and cross section profile, such as a straight channel member having at least one partially open longitudinal channel, into a curved channel member of predetermined curvature and of a predetermined cross section profile, comprising a forming member having a peripheral forming track of said predetermined curvature; a roller member having a circular track defined by a generatrix portions of which engage tangentially facing portions of said forming track, and defining therebetween the overall cross section profile of said secured channel member; the profile of the roller generatrix and the facing cross section profile of said forming track being so shaped that a relative motion between said forming member and said rolling member along said forming track brings successive peripheral elements of said roller track into engagement with successive peripheral portions of said forming track for forming said given channel member into said curved channel member while successive peripheral portions of said roller track and successive facing portions of said forming track define said predetermined channel cross section profile except for channel portions which are partially enclosed; means for holding affixed a portion of said given channel member to a portion of said forming member while another portion of said given channel member is confined between a generatrix of said roller track and the facing cross section profile of said forming track; means for causing a relative motion between said roller member and said forming member for thereby causing said channel member to

be deformed into said curved channel member; and at least one filler member extending through the partially enclosed channel portion of said channel member so as to prevent the deformation of the cross section area of said partially enclosed channel section, said filler member being so interconnected with said roller member as to cause said filler member to be maintained between the generatrix of said roller track and the facing portion of said track member while successive portions of said roller track are brought into engagement with successive portions of said forming track.

Among the objects of the invention is also an arrangement for producing a plurality of predeterminedly spaced predeterminedly dimensioned grooves along a peripheral wall region of an endless rail member having a peripheral wall section the dimensions of which are maintained within a certain degree of tolerance, for instance, a circular rail having a circular wall section the diameter of which varies within a tolerance of $\frac{1}{16}$ " and provided with equally spaced grooves the root of which has to be spaced from said wall section with a substantially higher degree of tolerance, for instance, of the order of .003", comprising an index member having a peripheral indexing region correlated to the peripheral region of said rail member and having along said indexing region a plurality of predeterminedly spaced registering position; means for holding said rail member in a predeterminedly aligned position relatively to said index member so that the said wall section and said peripheral wall region of said rail member is maintained in predetermined aligned position relatively to said index region; a carrier member arranged to be advanced and retained in different registering positions of said indexing member; a slider member slidably mounted on said carrier member; said slider member having a follower member adapted to be moved into engagement with said wall section in each of the registering positions of said carrier member; and a tool-guide element predeterminedly spaced from said follower member on said slider member for guiding a tool into engagement with the peripheral region of said rail member from which material is to be re-

The foregoing and other objects of the invention will be best understood from the following description of exemplifications thereof, reference being had to the accompanying drawings where-
in

Fig. 1 is a side view of a circular rail track of the invention;

Fig. 2 is a top view of a half section of the circular rail track of Fig. 1 showing the relationship thereof to the remainder of the circular rail track;

Fig. 2a is a top view corresponding to the solid line portion of Fig. 2 showing the manner in which the solid line portion of Fig. 2 is formed by bending an extruded straight channel bar of the required shape to a semicircular formation and removing the projecting ends;

Fig. 3 is a top plan view partially broken away of the novel circular rail track forming machine;

Fig. 4 is a cross-sectional view along line 4-4 of Fig. 3;

Fig. 5 is a cross-sectional view along line 5-5 of Fig. 3;

Fig. 6 is a cross-sectional view partly in elevation along line 6-6 of Fig. 3; and

Fig. 7 is a view partly in cross section along line 7-7 of Fig. 3.

The features of the present invention have been evolved in connection with the difficulties that arose in the manufacture of circular rail track rings for gun turrets of the type used in aircraft, and similar applications. Figs. 1, 2 and 2a illustrate one specific form of circular rail track formed by the machinery and methods of the present invention. As shown in the drawings, the circular rail track 20 is of a channel shaped profile or cross section. It has a cylindrical outer wall 21 provided with an inwardly extending circular rib 22 having an axially bent portion 23 forming with the adjacent portion of the cylindrical rail wall 21 a radially confined circular channel 24; a second radially extending rib 25; a third rib 26 provided along its inner periphery with equally spaced grooves or serrations 27 and having at an intermediate portion thereof an axially extending circular rib section 28 forming with the outer rail wall 21 a radially confined circular channel 29 and a fourth rib 31 having an axially extending circular rib section 32 forming with the rail wall 21 a radially confined circular channel 33.

It will be noted that the three rib members 22, 25 and 31 are shaped so as to provide in addition to the radially confined circular channels 24, 29 and 33 also inwardly open channel sections 34, 35. Circular rail channels of the cross section shown in Figs. 1, 2 and 2a, made of aluminum, are actually used for guiding a rotary gun turret of the general type described, for instance, in Patent 2,206,065.

Such circular aluminum rail rings are made of two semicircular sections and each semicircular rail ring section has to be made from an extruded straight channel bar of aluminum having the required cross section. The formation of such semicircular channel-shaped rail guide member from a straight extruded aluminum bar is connected with a great many difficulties.

In order to bend such extruded aluminum bar, it has to be softened by heat treatment and quenching, and when so softened by heat treatment, it remains soft only for about half an hour and it season-hardens and cannot be bent thereafter without repeating the heat treatment process.

Prior to the present invention, the forming of straight extruded aluminum bars into semicircular rings required highly skilled aluminum metal formers using appropriate arbors, mandrels, hammers, etc., for shaping a small part

of the rail ring at a time with a large number of heat treatments and about two days of labor so required to complete the formation of a single ring.

The alternative available method of making such rail rings by casting involved the use of heavy aluminum casting and subsequent machining of the casting to the accurate dimensions required for such ring with the consequent waste of aluminum and the use of critical machine tools.

The machinery and process of the present invention makes it possible to form straight extruded aluminum bars of the required accurate cross section into an accurate semicircular rail section with a single heat treatment process within less than half an hour, without modifying the profile of the cross section. One practical form of machinery for forming a straight bar of the required cross section into a semicircular rail track will now be described in connection with Figs. 3 to 7, illustrating one form of device for carrying out the process of the invention.

A generally circular forming block 41 provided with a centrally located fixed shaft member 42 is shown held in a horizontal position by suitably mounting the lower end of the shaft in a suitable pedestal 4. As shown in Fig. 4, the periphery of the forming block is provided with two exterior ribs 45, 46 and two intermediate circular ribs 47 shaped so that when a straight rail bar having a cross section profile shown in Fig. 1 is placed between the outer ribs 45, 46 of the forming block, the entire profile will be aligned with and confined within the outer ribs 45, 46 of the forming blocks with the two intermediate ribs 47 of the forming block interfitting with the radially open channel sections 34, 35, respectively.

A straight rail bar 50 is arranged to have one end thereof clamped to a peripheral portion of the forming block 41 by means of a clamping arm 51 having at its rear end two ears 52 pivotally mounted on a shaft section 53 extending through the height of the forming block 41. The inwardly facing side of the clamping arm 51 is so shaped and its surface is provided with teeth 54 so shaped that when the clamping end of the arm 51 is pressed inwardly against the end of the bar 50, a pull exerted on the bar in the direction of the arrow 55 will increase the clamping action exerted by the teeth 54 on the end of the bar.

The clamping end of the clamping arm 51 is held in its clamping position by the inward end of one or more locking bolts 61 threadedly mounted in a mounting member 62, the two ends of which are provided with stop shafts 63 pivotally engaging holes in two links 64 extending on the opposite sides of the forming block and pivotally mounted on a pivot shaft 65 extending through the forming block 41. A handle 66 extending from the mounting member 62 of the locking bolt 61 may be pivoted between an unlocking position indicated by the dotted line 66' to the locking position in which it is shown.

After tilting the arm 66 to the unlocking position 66', the two links 64 with the locking bolt 61 carried thereby may be tilted from the locking position shown to the position indicated by the dotted line 66' whereupon the locking arm 51 may be tilted outwardly on its pivots 53, the locking arm 51 having two stop pins 58 against which the two links 64 are swung when they are re-

turned from the open dotted line position 66' to the full line locking position shown.

There is further provided a forming or bending head designated generally as 70 comprising two arms 71 extending on the opposite sides of the forming block and having their inner ends pivotally mounted on the shaft portions 42 extending on the opposite sides of the forming block, the outer ends of the two arms 71 being joined by a junction plate 72 suitably secured as by screws 73 to the ends of the two arms 71 and having an outwardly projecting socket sleeve 74 in which is mounted the bending arm 75 which is used for turning the forming head 70 around the shaft 41 and performing the bending operation. Between the two arms 71 of the forming head 70 is located a forming roller 76 which is revolvably mounted on a shaft 77 having rectangular end portions slidably confined within slots 78 formed in the two head arms 71.

The junction plate 72 has suitably mounted therein two adjusting bolts 79 arranged so that by turning them inwardly the ends of the roller shaft 77 are pushed inwardly so as to bring the periphery of the forming roller 76 to the position where it lies substantially flush against the outer periphery of the two ribs 45, 46 so that the roller 76 and the cooperating facing portions of the periphery of the forming block 41 define accurately the cross sectional area of the profile which the bent bar has to assume when bent into semicircular shape as parts of it are being stretched and deformed.

The two forming head arms 71 serve also as a pivotal support for the opposite ends of a bending roller 81. The bending roller 81 is of somewhat smaller diameter than the bending roller 76 and it is located on the forming head in such a position that when the bending head 70 is rotated on its shaft from the position shown in Fig. 3 in the counter-clockwise direction indicated by the arrow, the bending roller 81 bends the straight bar 50 inwardly against the periphery of the forming block while the forming roller 76 moves along the periphery of the forming block thereby forcing successive elements of the straight bar to be stretched as it is being bent into circular shape while forcing and confining all the material of the bar within the required cross section provided between the elements of the forming structure so arranged.

The bending roller 81 is rotatably mounted on a shaft 82 having rectangular ends slidably rotated in slits 83 provided in lateral extensions 84 of the two arms 71, a junction plate 85 suitably secured to the two extensions 84 and adjusting bolts 86 serving to adjust accurately the position of the bending roller in a manner similar to the adjustment of the forming roller 76 described above.

In order to assure that the radially confined circular channel portions 24 of the bent rail track retain their accurate shape while the straight rail is being bent and stretched into its circular shape, there is placed in each radially confined channel 24, 29, 33 a short arbor member having a portion extending opposite the innermost line of the forming roller 76 so as to prevent any material of the rail body from being squeezed into the radially confined channel spaces.

In the arrangement shown, three such short arbor members 91, 92, 93 are provided for the three radially confined channels 24, 29, 33. Provision is also made to assure that as the forming head is rotated to bend successive portions of the straight channel bar into the required circular

shape, the several arbor members 91, 92, 93 are moved in unison therewith so as to be maintained continuously opposite the inwardly facing edge of the forming roller 76 in the position where the bent cross section of the channel member is given its final uniform shape, thus preventing any deformation of the inner cross section of the rail channels while the straight channel bar is bent into its circular shape.

10. In the arrangement shown, the three arbor members 91, 92, 93 are moved in synchronized relation with the forming roller 76 by connector elements in the form of strips 95 of metal, one end of which is affixed as by welding or riveting to an end portion of the arbor or filling member, and the other end of which is secured to a clamping element 95' and the several clamping elements 95' are secured to ribs 96 of a supporting member 98 arranged for mounting between portions of the lateral extensions 84 as by an interlinking pivot bolt 99 so that when the head 70 is rotated on the shaft 42 to advance the forming roller along the periphery of the forming block, the several arbor or filling members 91, 92, 93 are moved in synchronism therewith so that their center regions shall at all times face the generatrix of the forming roller 76 which engages the outermost peripheral portions of the forming block as the forming roller is being advanced along the periphery of the forming block.
15. As shown in the drawings, the several clamping elements 95' may be secured to the ribs 96 of the supporting block by pivot pins 95''. The arbor supporting block 98 may as shown be provided with additional holes 99' so that on removing the pivot bolt 99, the arbor support 98 may be mounted in a different adjusted position on the forming head structure.

Such forming machine makes it possible to bend a straight channel bar into a semicircular rail support of accurate dimensions. In order to form out of straight channel bars a semicircular structure, such as shown in Figs. 1 and 2, the bar has to be somewhat longer than the periphery of the semicircular formation in order to provide for the two end portions one of which is held clamped by the clamping arm 51 near the starting region of the forming operation, the other end of which remains at the other end of the bar after the bar has been bent and formed to provide the semicircular structure, the two straight end portions being then cut off.

It has been found that the extruded aluminum channel bar stock is oversize in some places as much as .020" or .025". To secure a more uniform circular rail structure, it was found desirable to true the various thicknesses of the wall of the straight extruded channel bar structure by a simple planning or end-mill operation.

It will be apparent to those skilled in the art that the novel principles of the invention disclosed herein in connection with specific exemplifications thereof will suggest various other modifications and applications of the same. It is accordingly desired that in construing the breadth of the appended claims they shall not be limited to the specific exemplifications of the invention described herein.

I claim:

1. In an arrangement for forming a given channel member of a given cross-sectional shape, such as a straight channel member having at least one partially open longitudinal channel, into a curved channel member of predetermined curvature and cross-sectional profile: a

forming member having an outwardly-facing peripheral forming track of said predetermined curvature and a cross-sectional profile corresponding to border portions of the cross-sectional profile of the side of the channel member having the channel; a roller member having a circular outer surface of a cross-sectional profile defined by a generatrix corresponding to the cross-sectional surface profile of the other side of the channel member, and defining with the facing portions of the forming track the overall cross-sectional profile of said curved channel member; the profile of the roller generatrix and the facing cross-sectional profile of said forming track being so shaped that a relative motion between said forming member and said rolling member along said forming track brings successive peripheral elements of said roller track into operative engagement with successive peripheral portions of said forming track for forming said given channel member into said curved channel member while successive peripheral portions of said roller track and successive facing portions of said forming track define said predetermined channel cross-sectional profile except for channel portions which are partially enclosed; a clamp structure movably connected to said forming member and movable to a position in which it clamps a portion of said given channel member to a portion of said forming member while another portion of said given channel member is confined between said roller and the forming track of said forming member; a substantially-rigid supporting structure movably connected to said forming member and rotatably supporting said roller member so that a relative motion between said supporting structure and said forming member causes said roller member to deform said channel member into said curved channel member; and at least one filler member extending through the partially enclosed channel portion of said channel member so as to prevent the deformation of the cross-sectional area of said partially enclosed channel section while said channel member is being deformed; and a link structure interconnecting said filler member with said supporting structure so as to cause said filler member to move along said roller track with said roller member so as to be maintained between the generatrix of said roller track and the facing portion of said track member while successive portions of said roller track are brought into engagement with successive portions of said forming track.

2. In an arrangement for forming a given channel member of a given cross-sectional shape, such as a straight channel member having at least one partially open longitudinal channel, into

a curved channel member of circular curvature and of predetermined cross-sectional profile: a forming member having an outwardly-facing peripheral forming track of said predetermined curvature and a cross-sectional profile corresponding to border portions of the cross-sectional profile of the side of the channel member having the channel; a roller member having a circular outer surface of a cross-sectional profile defined by a generatrix corresponding to the cross-sectional surface profile of the other side of the channel member, and defining with the facing portions of the forming track the overall cross-sectional profile of said curved channel member; the profile of the roller generatrix and the facing cross-sectional profile of said forming track being so shaped that a relative motion between said forming member and said rolling member along said forming track begins successive peripheral elements of said roller track into operative engagement with successive peripheral portions of said forming track for forming said given channel member into said curved channel member while successive peripheral portions of said roller track and successive facing portions of said forming track define said predetermined channel cross-sectional profile except for channel portions which are partially enclosed; a clamp structure movably connected to said forming member and movable to a position in which it clamps a portion of said given channel member to a portion of said forming member while another portion of said given channel member is confined between said roller track and the forming track of said forming member; a substantially-rigid supporting structure pivotally connected to said forming member and rotatably supporting said roller member so that a relative motion between said supporting structure and said forming member causes said roller member to deform said channel member into said curved channel member; and at least two flexibly-joined substantially-rigid filler members extending through the partially enclosed channel portion of said channel member so as to prevent the deformation of the cross-sectional area of said partially enclosed channel section while said channel member is being deformed; and a link structure interconnecting said filler member with said supporting structure so as to cause said filler member to move along said roller track with said roller member so as to be maintained between the generatrix of said roller track and the facing portion of said track member while successive portions of said roller track are brought into engagement with successive portions of said forming track.

JACOB D. STIRISS.
